Application September 23, 1957, Serial No. 685,685

6 Claims. (Cl. 20—16)

This invention relates to door closer apparatus and particularly to a novel apparatus wherein a torsion bar is utilized to provide torque for returning a door to a closed position.

In general, one aspect of the present invention invention includes a leaf hinge type of construction wherein a resilient bar forms the pivotal connection between the leaf portions of the hinges. In addition, the torsion bar is utilized to provide the torque required to close the door and to maintain the door in a closed position.

As another aspect, the present invention provides a jamb pivot type of construction whereby a door is hung in the center of the jamb, with a resilient torsion bar being disposed within the door along the pivotal axes thereof. The upper and lower ends of the torsion bar are extended beyond the upper and lower edges of the door and inserted into sockets carried by the door frame whereby the torsion bar and sockets form the pivotal connection for mounting the door to its frame. In addition, the torsion bar is anchored to the frame at one of said extended ends and said bar is also anchored to the door whereby opening of the door twists the torsion bar such that upon release of the door the torsion bar exerts a torque on the door and closes same.

As still another aspect, the present invention provides a novel mounting apparatus for a center hung torsion bar type door mounting, which apparatus facilitates hanging a door and is adapted for the application of pre-loaded torque to the torsion bar which forms a pivotal mounting for the door and also urges said door towards a closed position.

It is therefore an object of the present invention to provide a door closing apparatus wherein a resilient bar provides both means for pivotally mounting the door and means for returning the door to a closed position.

It is another object of the present invention to provide a novel leaf hinge type door mounting which includes means for returning the door to a closed position.

It is still another object of the present invention to provide a novel jamb socket type mounting means for a door which includes means for returning the door to a closed position.

It is another object of the present invention to provide door mounting apparatus of the type described which is either completely or substantially hidden from view.

It is still another object of the present invention to provide a novel mounting apparatus for a center hung type door which apparatus facilitates the hanging of a door and is adapted for the application of a pre-loaded torque to the torsion bar that forms the hanging pivot and urges the door towards a closed position.

Further objects and advantages of the present invention will be apparent from the following description, reference being had to the accompanying drawings wherein preferred forms of embodiments of the invention are clearly shown.

In the drawing:

Figure 1 is a front elevational view of a door mounting

and closing apparatus constructed according to the present invention and constitutes one aspect thereof;

Figure 2 is a top sectional view of the apparatus of Figure 1 with the section being taken along line 2—2 of Figure 1;

Figure 3 is a front elevational view of a second door mounting and closing apparatus constructed according to the present invention and constituting a second aspect thereof;

10 Figure 4 is a top sectional view of the apparatus of Figure 3 with the section being taken along the line 4—4 of Figure 3;

Figure 5 illustrates a head jamb portion of a door mounting apparatus constructed according to the present invention;

15 Figure 6 illustrates a floor portion of a door mounting apparatus used in connection with the apparatus of Figure 5;

Figure 7 is a sectional view of a portion of the apparatus of Figure 5, the section being taken along the line 7—7 of Figure 5;

Figure 8 is a sectional view of the portion of the apparatus of Figure 6 with the section being taken along the line 8—8 of Figure 6;

25 Figure 9 is a sectional view illustrating the head jamb portion of another door mounting apparatus constructed according to the present invention and comprising another aspect thereof;

Figure 10 is a sectional view of a floor portion of the 30 door mounting apparatus of Figure 9;

Figure 11 is a sectional view of a portion of the apparatus of Figure 9; the portion being taken along the line 11—11 of Figure 9;

Figure 12 is a sectional view of a portion of the apparatus of Figure 9 the section being taken along the line 12—12 of Figure 9;

Figure 13 is a sectional view of a portion of the apparatus of Figure 10, the section being taken along the line 13—13 of Figure 10; and

40 Figure 14 is a sectional view of a portion of the apparatus of Figure 10, the section being taken along the line 14—14 of Figure 10.

Referring in detail to the drawing, Figure 1 illustrates a wall indicated generally at 20 which forms the frame means for a door including top frame member 21, jamb member 22, floor member 23, and side member 24. A door 26 is hung on three butt hinges indicated generally at 28, 29, and 30. Upper hinge 28 includes a door leaf 32 and a jamb leaf 33. Similarly, door leaves 35 and 37 form the portions of the other two hinges 29 and 30. A torsion bar 40 is extended through the bearing holes formed by the leaf portions of the hinges thereby providing the pivotal connection between the two leaf portions of each hinge.

55 To provide the necessary torque action for closing door 26, torsion bar 40 is anchored to one of the door leaves of one of the hinges and also to one of the jamb leaves for another one of the hinges.

As one arrangement torsion bar 40 may be anchored at its upper end to door leaf 32 of upper hinge 28, with torsion bar 40 passing freely through hinge 29 and having its lower end anchored to jamb leaf 37 of lower hinge 30. As another arrangement the upper end of torsion bar 40 is anchored to jamb leaf 33 of an upper hinge 28, with the torsion bar passing freely through hinge 29

60 and having its lower end anchored to door leaf 36 of lower hinge 30. As another arrangement torsion bar 40 can be secured between a door leaf and a jamb leaf for hinges 28 and 29 respectively, or between a door leaf and a jamb leaf of hinges 29 and 30 respectively. Or, if desired, torsion bar 40 can be secured to a door leaf of hinge 28, a jamb leaf of hinge 29, and a door leaf of

hinge 30, respectively. As an alternative, torsion bar 40 can be secured to a jamb leaf of hinge 28, a door leaf of hinge 29, and a jamb leaf of hinge 30.

As still another alternative, for the apparatus of Figure 1, door 26 can be hung on only the two butt hinges 28 and 30, the intermittent hinge 29 being omitted.

The torsion bar 40 is then secured to either the door leaf of hinge 28 and the jamb leaf of hinge 30 or to the jamb leaf of hinge 28 and the door leaf of hinge 30.

In operation of the apparatus of Figure 1, when door 26 is opened torsion bar 40 is twisted about its longitudinal axis. The torsional stress thus induced will cause the door to close when the door is released. In addition, torsion bar 40 is anchored to the hinge portions with a suitable portion of the twist being present in torsion bar 40 when door 26 is in the closed position against a stop 42 as seen in Figure 2. Thus it will be understood that the residual torque, i.e. the torque remaining in torsion bar 40 when the door is closed, serves to constantly urge door 26 against stop 42. With this arrangement the residual torque provides an initial resistance to opening of the door.

It will be understood that torsion bar 40 may be utilized as hinge pins, in the manner illustrated, or it may be utilized in conjunction with a conventional hinge pin arrangement.

Reference is next made to Figures 3 and 4 wherein a second aspect of the present invention is illustrated. The construction illustrated in Figure 3 includes a door 26-A provided with a longitudinally disposed hole 50 through which is extended a resilient torsion bar 40-A. An upper frame portion 21-A carries a head jamb mounting apparatus 52, Figure 5, that forms a socket into which is inserted an upper end 53 of torsion bar 40-A. Floor member 23-A carries a floor mounting apparatus 54, Figure 6, into which a lower end 55 is inserted. The mounting apparatus 52, 52-A, and 54 are illustrated in Figures 5 through 14 and described in detail later herein.

As one arrangement of the apparatus of Figure 3, door 26-A is hung in the center of jamb 22, with torsion bar 40-A having its upper end 53 and lower end 55 inserted into head jamb mounting apparatus 52 and floor mounting apparatus 54 respectively. The upper end 53 of torsion bar 40-A is anchored to upper frame portion 21-A at head jamb mounting apparatus 52, and the lower end of torsion bar 40-A is anchored to door 26-A at floor mounting apparatus 54. Hence when door 26 is opened torsion bar 40-A will be twisted, the torsional stress thus induced being available for closing the door.

As an alternative arrangement for the apparatus of Figures 3 and 4, door 26-A is again hung in the center of a jamb 22, as illustrated, the upper end 53-A of torsion bar 40-B being freely inserted into a head jamb mounting apparatus 52-A, Figure 9, which apparatus forms a bearing for rotatably supporting upper end 53-A of the torsion bar. The upper end of the torsion bar is also anchored to door 26-A. The lower end 55 of the torsion bar passes freely through the door bottom and is anchored to floor mounting apparatus 54-A, Figure 10. Hence it will be understood that upon opening of door 26, torsion bar 40-B is twisted, the torsional stress thus induced serving to return the door to a closed position when the door is released. Here again, as was the case of the apparatus of Figures 1 and 2, a stop 42 is provided for engagement by the door when the door is in the closed configuration. Moreover, torsion bar 40-A or 40-B is mounted in a slightly twisted configuration when it is secured to its previously described anchored connection. Hence, a residual torque remains in torsion bar 40-A or 40-B when the door is closed, thus holding the door firmly against stop 42 to provide a resistance to opening of the door.

Reference is next made to Figures 5 through 8 which illustrate in detail one of the previously mentioned door

mounting apparatus which comprises one aspect of the present invention. Such apparatus includes a head jamb portion 52 and floor mounting apparatus 54.

With particular reference to Figure 5, upper frame member 21-A has a recess 61 in which is mounted a housing 62. A plurality of screws 86 secure housing 62 to frame member 21-A. A socket 75 is mounted for vertical sliding movement in housing 62. Lower end of socket 75 has a square hole 98 for receiving a square upper end 53 of torsion bar 40-A. Socket 75 is raised or lowered by means of a lever 68 pivotally mounted to the inner wall 62 at pivot 69. One end of lever 68 is engaged by a screw 67 carried in a threaded hole in housing 62. The other end of lever 68 passes freely through a vertical slot 71 in housing 62 and it extends into a hole 77 in the side wall of socket 75. Hence it will be understood that when screw 67 is screwed upwardly socket 75 is lowered, and when screw 67 is moved downwardly socket 75 is raised.

The upper edge of door 26-A includes a recess 63 and an upper bearing plate 65 is fastened in the bottom of this recess by means of a plurality of screws 86. The uppermost round portion of torsion bar 40-A extends freely through a bearing 88 carried by bearing plate 65, and the upper end 53 of torsion bar 40-A is of a square cross section conforming with the cross sectional shape of hole 98 in the lower end of socket 75.

From the above it will be understood that when socket 75 is in a raised position, above the lower surface of housing 62, the top of door 26-A can be moved into position in the center of the jamb whereby hole 98 in socket 75 is axially aligned with end 53 on torsion bar 40-A. Screw 67 can then be screwed upwardly whereby socket 75 is moved downwardly and into anchoring engagement with upper end 53 of torsion bar 40-A.

Referring particularly to Figure 6, previously mentioned floor mounting apparatus 54 includes a floor plate 85 secured to floor 23-A by means of a plurality of screws 86. A combination of radial and thrust bearing 84 is carried by floor plate 85 and rotatably receives a projection 99 from the bottom of a lower door plate 83.

The square lower end 55 of torsion bar 40-A is adjustably secured to the lower portion of the door in such a manner that pre-loaded torque can be applied to torsion bar 40-A at the time the door is being hung. A ratchet 80 is positioned in a recess 102 in the bottom of door 26-A and includes a square hole 82 conforming in cross-sectional shape with the square lower end 55 of torsion bar 40-A. Ratchet 80 is keyed to lower door plate 83 in various positions of rotation, by means of a pin 78 that can be selectively inserted into any one of the plurality of holes 79, or drilled radially inwardly into the periphery of ratchet 80 as is best seen in Figure 8. With reference to Figure 6 the outer end of pin 78 is engaged by an upwardly projecting shoulder 90 formed on the upper surface of lower door plate 83. In assembling the apparatus of Figures 5 through 8, hole 60 is provided in the door with such hole being of sufficient diameter to provide clearance space between the outer surface of torsion bar 48 and the wall of hole 60. Top bearing plate 65 is then fastened in recess 63 in the top of the door. Ratchet 80 is then placed over the lower end 53 of the torsion bar and the torsion bar is inserted into hole 60 in the door so that the top of square upper end 53 of the torsion bar is flush with the top of the door. Lower door plate 83 is then attached to the bottom of the door so that a round blind hole 100 in plate 83 fits over a round tang 101 on the bottom end of the torsion bar. Hence it will be understood that lower door plate 83 serves to retain the torsion bar in hole 60 of the door and blind hole 100 maintains the torsion bar in axial alignment with top bearing 88.

The door is hung by moving socket 75 to an upper position, as previously described. The door, in a partially open position, is inserted into position so that the

bottom pivot projection 99 is seated in bearing 84 carried by floor plate 85. With the door still in a partially open position, the top of the door is moved inwardly so that the top square portion 53 of the torsion bar is in axial alignment with socket 75. An adjusting pin, not illustrated, is next inserted through an access opening in the side of the bottom of the door, with the end of such adjusting pin being inserted into one of the radial holes 79 in ratchet 80. By means of the adjusting pin the ratchet 80 and torsion bar are rotated to a position wherein the square upper end 53 of the torsion bar lines up with the square hole 98 in the bottom of socket 75. Screw 67 is now screwed upwardly whereby lever 68 extends socket 75 downwardly over the square upper end of torsion bar 40-A.

The door being now hung in the doorway opening, the previously mentioned adjusting pin is utilized to wind ratchet 80 and torsion bar 40-A to provide the desired amount of pre-loaded torque whereby door 26-A is urged against the previously mentioned stop 42 illustrated in Figure 3. Previously mentioned pin 78 is next inserted into one of the radial holes 79 and ratchet 80. When the adjusting pin is removed, the outer end of pin 78 will bear against projection 90 carried by lower door plate 83.

It will now be understood that the torsion bar will normally be subjected to a pre-loaded torque restrained at the bottom by ratchet 80, pin 78, shoulder 90, lower door plate 83, and door 26-A, with this pre-loaded torque being resisted at the top by means of socket 75 which is restrained against rotation by lever 68 at slot 77. Said lever 68 is mounted to housing 62 which housing is in turn mounted to upper frame member 21-A.

In operation of the apparatus of Figures 5 through 8, when the door is open it pivots freely at the top above torsion bar 40-A. Bearing 88 forms a pivot between the top of the door and the round portion of the top of the torsion bar. At the bottom of the door lower door plate 83 pivots freely on bearing 84 whereby shoulder 90 on lower door plate 83 exerts a force against the side of pin 78 whereby ratchet 80 is rotated and torsion bar 40-A is twisted about its longitudinal axis. Hence torsional energy is stored in the torsion bar which energy is utilized to close the door when the door is released. Upon release of the door ratchet 80 is rotated whereby pin 78 applies force to shoulder 90 on lower door plate 83. The torsional energy is then transmitted through lower door plate 83 to door 26-A.

Reference is next made to Figures 9 through 14 which illustrate another door closing apparatus comprising another aspect of the present invention. This apparatus includes the previously mentioned head jamb mounting apparatus 52-A and floor mounting apparatus 54-A.

Referring particularly to Figure 9, head jamb mounting apparatus 52-A includes the housing 62 and the lever and socket mechanism contained therein, of the same construction previously described in connection with Figure 5. The socket 75-A of Figure 9 differs from the previously described socket 75 in that the lower end of socket 75-A carries a bearing 103 having a round hole 92 for rotatably receiving a round upper end 53-A of torsion bar 40-B. Such round upper end 53-A and round bearing hole 92 form an anti-friction pivot for the upper end of door 26-B.

Referring particularly to Figure 10, a lower square end 55-A on torsion bar 40-B is inserted into a square hole 105 formed in a floor anchor plate 85-A, the latter being secured to floor 23-A by a plurality of screws 86. The combination radial and thrust bearing 84 is mounted on floor anchor plate 85-A and receives a downward projection 107 on lower floor plate 83-A. As is best seen in Figure 13, the lowermost round portion of torsion bar 40-B extends through a round bearing 94 carried by lower door plate 83-A. Hence it will be understood that the bottom of the door 26-B can pivot freely about the lowermost round portion of torsion bar 40-B.

Referring particularly to Figures 9 and 12 the upper end of torsion bar 40-B includes a portion of square cross-section which fits into a square hole 82 through the center of ratchet 80. Pin 78 is inserted into one of a plurality of radial holes 79 in the periphery of ratchet 80, with the outer end of pin 78 being engaged by a shoulder 90, in upper door plate 65-A. It will be noted that upper door plate 65-A is mounted to door 26-B by a plurality of screws 86.

10 In assembling the apparatus of Figures 9 through 14 a hole 60 is formed longitudinally through the door and a recess 63 is provided in the top of the door in the manner illustrated. Top door plate 65-A is fastened in recess 63 and between door plate 83-A is secured to the bottom edge of the door. Ratchet 80 with its square central hole 82 is next mounted on square portion 91 on the upper end of the torsion bar and the torsion bar is inserted in the hole 60 in the door. The lower end of the torsion bar is extended through bearing 94 carried by lower door plate 83-A.

15 With socket 75-A in a retracted position, as previously described, and with the door in a partially open position, the square lower end 55-A of the torsion bar is inserted into square hole 105 in floor anchor plate 85-A. The round top portion 53-A of the torsion bar is next axially aligned in a round bearing hole 92 in socket 75-A. Hence screw 67 is screwed upwardly whereby socket 75-A moves downwardly into surrounding relationship with round end 53-A of the torsion bar.

20 An access panel, not illustrated, on the side of the door at the top is removed to provide access to ratchet 80. An adjusting pin, not illustrated, is next inserted into one of the radial holes 79 whereby the ratchet and torsion bar can be wound to provide the desired amount of pre-loaded torque. A pin 78 is next inserted into one of a plurality of radial holes 79 in ratchet 80 such that when the adjusting pin is removed pin 78 will bear against shoulder 90 on upper door plate 65-A.

25 With reference to the operation of the apparatus of Figures 9 through 14, as the door is opened shoulder 90 applies a force to pin 78 and ratchet 80 whereby the top of the torsion bar is rotated. It will be understood that the round upper end 53-A of the torsion bar will pivot freely in the bearing 92 of socket 75-A. Hence it will be understood that the torsion bar acts as a pivot for the top of the door. At the bottom, the lower square end 55-A of the torsion bar is anchored in the square hole 105 in floor anchor plate 85-A. It will be understood, however, that the lower end of the door pivots freely about the torsion bar at the bearing 94 whereby the torsion bar forms a lower pivotal mounting for the door.

30 When the door is opened twisting action is applied to torsion bar 40-B through upper door plate 65-A, shoulder 90, pin 78, and ratchet 80. At the bottom rotation of the torsion bar is resisted by floor anchor plate 85-A secured to floor 23-A. Hence it will be understood that opening of the door serves to store torsional energy in torsion bar 40-B, which energy is utilized to effect closing action when the door is released.

35 While the forms of embodiments of the present invention as herein disclosed constitute preferred forms, it is to be understood that other forms might be adopted, all coming within the scope of the claims which follow.

We claim:

40 1. The combination of a door frame including an upper hinge socket and a lower hinge socket; a door including a hole formed through the door from the upper edge to the lower edge thereof, said hole being coextensive with the pivotal axis of the door; a resilient bar extended through said hole and having an upper end inserted in said upper socket and a lower end inserted in said lower socket, said bar including an anchor connection with said frame at one of said sockets and an anchor connection with said door at a location spaced from said first mentioned anchor connection; means on said frame forming

a movable mounting for said upper hinge socket for extending said upper hinge socket beyond said upper edge, into said hole and around said upper end.

2. The combination of a door frame including an upper hinge socket and a lower hinge socket; a door including a hole formed through the door from the upper edge to the lower edge thereof, said hole being coextensive with the pivotal axis of the door; a resilient bar extended through said hole and having an upper end inserted in said upper socket and a lower end inserted in said lower socket, said bar including an anchor connection with said frame at one of said sockets, an anchor connection with said door at a location spaced from said first mentioned anchor connection; means for adjustably rotating one of said anchor connections relative to the other of said anchor connections for twisting said resilient bar; means on said frame forming a movable mounting for said upper hinge socket for extending said upper hinge socket beyond said upper edge, into said hole and around said upper end and stop means for said door, said resilient bar being in a twisted configuration when said door is against said stop means.

3. A door construction comprising, in combination, frame means including an upper frame member, a lower frame member, and a jamb member; a door including an upper edge, a lower edge, a side edge, and a hole formed through the door from said upper edge through said lower edge; a socket plate carried by the door-confronting surface of one of said upper and lower frame members, said socket plate forming a first socket and a first bearing portion; a second socket movably mounted within the door-confronting edge of the other of said upper and lower frame members; a resilient bar extended through said hole and connected to said door and disposed along the pivotal axis thereof, the ends of said bar being disposed in said sockets, one of said ends being anchored to said socket plate and forming a second bearing portion in engagement with said first bearing portion and means for moving said second socket between a first position within one of said frame members to a second position wherein said second socket extends into said hole and engages an end of said resilient bar.

4. A door construction comprising, in combination, frame means including an upper frame member, a lower frame member, and a jamb member; a door including an upper edge, a lower edge, and a hole formed through the door from said upper edge through said lower edge a side edge; a first socket movably mounted on the door-confronting surface of one of said upper and lower frame members a second socket formed by a socket plate spaced from said first socket and secured to said door; a resilient bar extended through said hole and disposed along the pivotal axis thereof, the ends of said bar being disposed in said sockets, one of said ends being anchored to said

- socket plate; and stop means for said door, said door being maintained against said stop by residual torque exerted by said bar a bearing plate including a bearing portion on the door confronting surface of the other of said upper and lower frame members; a second bearing portion on said door and in engagement with said first bearing portion and means for moving said first socket into said hole and into engagement with the other of said ends of said resilient bar.

5. A door construction comprising, in combination, frame means including an upper frame member, a lower frame member, and a jamb member; a door including an upper edge, a lower edge, and a side edge; a first door mounting means adjacent said upper edge and including a socket member secured to said upper frame member; a second door mounting means adjacent said lower edge and including a bearing member secured to said lower frame member; a resilient bar forming a pivotal connections with said socket member, said bar including an anchor connection with said bearing member and an anchor connection with said door; and means on said upper frame member for extending said socket member beyond said upper edge of said door and into connection with an upper end of said resilient bar.

6. A door construction comprising, in combination, frame means including an upper frame member, a lower frame member, and a jamb member; a door including an upper edge, a lower edge, and a side edge; a first door mounting means adjacent said upper edge and including a socket member secured to said upper frame member; a second door mounting means adjacent said lower edge and including a bearing member secured to said lower frame member; a resilient bar forming a pivotal connection with said socket member, said bar including an anchor connection with said bearing member; and means forming an adjustable connection between said resilient bar and said door for selectively providing various amounts of residual torque in said bar when said door is in a closed position; and means on said upper frame member for extending said socket member beyond said upper edge of said door and into connection with an upper end of said resilient bar.
